UNITED STATES PATENT OFFICE.

JAMES C. MEEM, OF BROOKLYN, NEW YORK, ASSIGNOR OF ONE-HALF TO FREDERICK L. CRANFORD, OF BROOKLYN, NEW YORK.

CAISSON.

1,246,136.

Specification of Letters Patent. Patented Nov. 13, 1917.

Application filed October 4, 1916. Serial No. 123,659.

To all whom it may concern:

Be it known that I, JAMES C. MEEM, a citizen of the United States, residing at Brooklyn, in the county of Kings and State 5 of New York, have invented certain new and useful Improvements in Caissons, of which the following is a full, clear, and exact specification.

This invention relates to caissons, and has 10 particular reference to improvements in what are commonly known as airless caissons or shields whereby it is desired to excavate below the ground water level without the use of compressed air for holding back 15 the water. Such caissons are useful for underpinning buildings, foundations, piers, etc. The caisson of this invention is capable of being driven in a downward or forward direction as the excavation proceeds, and 20 permits the excavated material to be removed through the top. The sides of the caisson of this invention are made in the form of interlocking sheet piles which slide one on the other and can be driven from 25 their upper or rear ends, while within the sheet piling and slidably attached thereto is an adjustable top through which the material is passed as it is excavated. For working in dry or solid material where there are 30 no quicksands, or similar materials subject to flow, the excavation proceeds in the usual way, but if quicksand, etc., is likely to flow suddenly into the caisson or shield, the top has doors capable of being quickly closed. 35 The soft flowable material may then be removed from below the top, through a pipe. Thus, the boiling of the material into the caisson can be quickly checked before it has proceeded far enough to cause a general sub- 40 sidence of the earth surrounding the caisson, and possible collapse of buildings thereon, and the material can be removed through the top of the caisson while it is simultaneously driven through the soft place. 45 In the accompanying drawings, Figure 1 is a vertical cross section of a caisson or shield embodying the invention, and

Fig. 2 is a transverse cross section.

1 represents interlocking sheet piles having sharpened edges 2 and preferably sheathed as at 3, having enlarged upper ends 4 which are driven by a hammer or pile driver as the excavation proceeds. As shown in Fig. 2, the sheathing 3 may be also 50 interlocked, so that external pressure is re-

sisted, and also tightness of the joints maintained. The sheathing 3 extends backward beyond the ends of the piling so as to form a tail 12 which overlaps the lining or lagging 5, or the permanent structure in case of 60 a vertical tunnel. The latter is set as the sides are driven forward. Mounted internally within the sides 1 is a top or bulkhead forming a closure and consisting of a cylindrical or guiding portion 6 sliding on the 65 piling, and a conical top portion 7. The sliding movement is limited by slots 8 and pins 9 on the piling. 10 are adjusting bolts carried by the adjustable guiding portion 6, and capable of being contracted or expanded 70 to insure a tight sliding fit. 11-11 are doors formed in the conical cover, which drop open by gravity in a vertical caisson and close automatically when the material from outside boils up within the caisson 75 body. In a horizontal caisson or shield, the doors will be normally open and closed by the material boiling in, if the men fail to close them when they leave. The upper end of the conical top is provided with an external reinforced driving shoulder 13, which is driven by a gravity operated hammer 14, as the excavation proceeds. 15 is a central pipe or casing, which extends down through 80 the center of the sliding conical top and is 85 normally closed above the top. The pipe can be used for pumping out water or jetting out soft material, while more solid material can be removed through the doors. 16 is a stop carried by the pipe 15 for limiting 90 the movement of the top.

In case of boiling of material up into the caisson, it will be stopped at the top by the closing of the doors 11, the pipe 15 being 95 already closed. Of course the men will notice the material commence to boil in and will have time to escape through the doors, the doors closing automatically after them in case they should neglect to close them. In case the space below the top should entirely fill up with the material, the top might be pushed back to the limit of its reciprocating movement, but would then be stopped by the top striking the enlarged portions 4 of the sheet piling. While the 105 doors remain closed, the material which has boiled into the caisson can be pumped out or otherwise removed, while the sides are driven downward to firm material, and then the men can reenter and excavate in the 110

- usual manner. Also, a jet can be used to clear out the material. The caisson can be used without the top and will be found very advantageous owing to its strength and 5 tightness. Also, a continuous cylindrical shield can be used with the slidable top. It will be understood that as the sides are driven forward, the extended interlocking portion of the sheathing acts as a tail and 10 bears on the previously completed section of the tunnel or pit, and the next section of the tunnel can then be placed in the space left by the piles. If used for erecting piers or foundations, or underpinning, the entire 15 space can be filled up with the permanent structure, and the caisson can either be left in the ground or withdrawn. If withdrawn, the space can be filled up with grout or other filling.
- 20 Various modifications and changes may be made in the specific construction herein described without departing from the scope of the appended claims.
- Having thus described my invention, what 25 I declare as new and desire to secure by Letters Patent of the United States is:—
1. A caisson comprising a tubular driving portion composed of interlocking sheet piling, a top sliding therein, and interlocking 30 sheathing constituting a tail extending rearwardly of said driving portion.
  2. A caisson comprising a segmental driving portion, a top slidable therein on the segmental driving portion, and a pipe passing 35 through said top for permitting removal of material.
  3. A caisson comprising a driving portion, a top slidable therein and having a door for the removal of material, and a normally 40 closed pipe passing through said top for removing fluid material independently of said door.
  4. A caisson comprising a driving portion, a top slidable therein, and having a normally 45 open self-closing door for the removal of material, and a pipe passing through said top for removing fluid material independently of said door.
  5. A caisson comprising a driving portion 50 composed of longitudinally extending interlocking piles, a top within said piles and slidably mounted therein, and means for expanding the guiding portion of said top to form a sliding fit between the top and the 55 piles.
  6. A caisson comprising a driving portion, a top slidably mounted therein, and having an expandable guiding portion.
7. A caisson comprising a driving portion, a top slidably mounted therein, and separate means for driving said top. 60
8. A caisson comprising a driving portion, a conical top sliding therein, a cylindrical guiding portion carried by said top and bearing on the interior of said caisson, and a pipe within the caisson and extending through said top. 65
9. A caisson comprising a driving portion, a conical top sliding therein, and having a door, a cylindrical guiding portion carried by said top and bearing on the interior of said caisson, and a pipe within the caisson and extending through said top. 70
10. A caisson comprising a driving portion, a conical top therein having a cylindrical guiding portion sliding on the interior of said caisson, a pipe extending through said top and having sliding engagement therewith, and a self closing door in said conical top. 75
11. A caisson comprising a driving portion, a conical top therein having a cylindrical guiding portion having limited sliding movement on the interior of said caisson, a pipe extending through said top and having sliding engagement therewith, and a self closing door in said conical top. 80
12. A caisson comprising a series of interlocking piles arranged in cylindrical formation and adapted to be driven forward individually, each pile having a sheet metal sheath on its outer face with one end bent to form a cutting edge and the other end projecting rearwardly to form a tail. 85
13. A caisson comprising a series of interlocking piles arranged in cylindrical formation and adapted to be driven forward individually, each pile having a sheet metal sheath on its outer face with one end bent to form a cutting edge and the other end 90 projecting rearwardly to form a tail and a closing top slidably mounted within said piles. 100
14. A caisson comprising a series of interlocking piles arranged cylindrically, each with a driving head at its rear end and each pile having a sheet metal external sheath bent around the forward end to form a cutting edge and projecting rearwardly to form a tail. 105

In testimony whereof I affix my signature.

JAMES C. MEEM.
